UNITED STATES PATENT OFFICE

CHARLES B. REYNOLDS, OF LA HABRA, CALIFORNIA

JET-NOZZLE APPARATUS

Substitute for abandoned application Serial No. 719,006, filed June 9, 1924. This application filed September 26, 1928. Serial No. 308,536.

This invention is a pump jet nozzle apparatus and consists of the novel features herein shown, described and claimed, and this application is a substitute for my application Serial Number 719,006, filed June 9, 1924, and abandoned.

An object is to make a nozzle apparatus having a straight smooth central flow opening and having an annular inclined slot or orifice for discharging a power medium into the flow opening, there being an annular chamber from which the slot leads, and means for conducting the power medium to the chamber.

Another object is to make a power nozzle apparatus which may be used for pumping liquid out of sump holes and the like, and which may be used for mixing two fluids together and for various other purposes.

Another object is to make a nozzle having a smooth flow opening for driven material and an annular angular orifice for discharging driving material into the driven material so as to move the driven material through the flow opening.

Other objects and advantages will appear from the specification and drawings.

The drawings illustrate a pump jet nozzle apparatus embodying the principles of my invention and showing the apparatus set up in various ways for various purposes.

Figure 1 is a sectional elevation of a pit and a sectional elevation of the pump jet nozzle apparatus set up to empty the pit of water, oil or the like.

Fig. 2 is a view analogous to Fig. 1 and showing a modification of the construction of the pump jet nozzle.

Fig. 3 is a view analogous to Figs. 1 and 2 and showing the nozzle set up with the intake at the top.

Fig. 4 is a fragmentary sectional detail showing the nozzle set up horizontally.

Fig. 5 is a sectional detail showing a second modified form of the nozzle.

The details of construction and operation shown in the drawings are as follows:

Referring to Fig. 1, the main frame of the nozzle consists of a lower casting 1 and an upper casting 2 having internally screw

threaded nipples 3 and 4 in a straight line. The castings 1 and 2 are finished upon their meeting faces and are connected together by flanges 5 and 6 and bolts 7 inserted through the flanges. In order to break the joint between the meeting faces of the castings a flange 8 extends from the casting 1 into a seat in the casting 2. A bell-shaped intake member 9 is screwed into the nipple 3 so as to produce a flaring mouth 10 and a straight passage 11 in line with a straight passage 12 in the casting 1. The lower nozzle member 13 is seated downwardly into the casting 1 and has a straight central passage 14 in line with the passages 11 and 12 and has a beveled outer face 15 leading to the upper end of the passage 14. An annular chamber 16 is formed in the casting 1 around the nozzle member 13. An upper nozzle member 17 is seated in the lower face of the casting 2 and held in place by screws 18 and has a passage 19 in line with the passages 11, 12 and 14 and in line with the passage 20 through the casting 2.

The lower corner of the second nozzle member 17 is beveled to form a face 21 at the opposite side of the annular slot or orifice 22 from the face 15. The bevels of the faces 15 and 21 are divergent from the outlet end of the slot 22 downwardly toward the chamber 16 so that the slot 22 will be wider at its inlet than at its outlet. An elbow 23 is screwed into the nipple 4 and has a passage 24 in line with the passages 11, 12, 14, 19 and 20 and a discharge pipe 25 is screwed into the elbow 23 and has a passage 26 communicating with the passage 24.

It is of special importance that the passages 11, 12, 14, 19, 20, 24 and 26 be all of the same size so as to make a smooth passage having no protuberances or pockets to catch material moving through the passages.

An internally screw threaded nipple 27 is formed integral with the casting 2 and has a passage 28 leading downwardly to the chamber 16. A pipe 29 which may be of any desired height is screwed into the nipple 27, an elbow 30 is screwed upon the pipe 29, and the pipe 31 is screwed into the elbow 30, there being a gate valve 32 incorporated into the pipe 31 and operated by hand lever 33 having a

100

pawl 34 to engage a sector 35. A retractile coil spring 36 connects the lever 33 to the pipe 31, the tension of the spring being exerted to hold the gate valve closed.

5 The pump jet nozzle apparatus thus constructed is mounted in a pit 37 which may be a sump hole, a cellar, a basin, or the like, and the pit 37 may be filled with water, oil and water, mud, slush, or the like, which will readily flow through the outlet passage from the intake 9.

10 Any desired fluid power such as water or the like, may be supplied to the pipe 31 under a desired power or pressure and when the lever 33 is operated to open the valve 32 a power medium will pass through the slot 22 and force the liquid of the pit upwardly and outwardly through the discharge pipe 25. The angle of discharge of the nozzle 22 15 relative to the flow opening may be varied considerably. As shown in the drawings, the face 21 is at an angle of 45° relative to the axis of the flow opening considering the passages 11, 12, 14, 19, 20, 24 and so 20 on, and this angle may be greater or less to suit the conditions under which the nozzle is to be used, the only requirement being that the angle shall discharge the power medium in the same general direction as the direction 25 of flow.

20 It will be seen from Fig. 1 that the fluid supply pipe 31 is at a higher elevation than the situation of the nozzle and the discharge pipe 25 and through the medium of the controlling valve in the pipe 31 a means is provided for controlling the flowing of a fluid under a pressure much higher than the hydrostatic head of the liquid to be pumped at the position of the nozzle. This develops a 30 jet of high velocity through the nozzle and elevates the water from the pit 37. The pipe 29 may be of any suitable length to give sufficient height to effect the desired hydraulic head or if necessary sufficient pressure may 40 be given by direct pumping.

45 Referring to the modification shown in Fig. 2, the castings 38 and 39 are finished to form the power medium outlet slot 40 and the castings are connected by flanges 41 and 50 42 and bolts 43. Pipe coupling flanges 44 and 45 are formed integral with the castings 38 and 39 and the pipe flange 46 is bolted to the flanges 44 and 45.

55 The pipe line 47 is tapped horizontally into the pipe flange 46 and the valve 48 controls the flow of power medium through the pipe line 47. The bell-shaped intake member 49 is screwed upon a nipple projecting from the casting 38 and the elbow 50 is screwed 60 upon a nipple projecting from the casting 39, the parts being all arranged and finished to make a straight smooth flow opening 51.

65 Referring to Fig. 3, the construction is substantially the same as shown in Fig. 2, except that the nozzle is set bottom upward so

that the intake member 49 is at the top and the outlet pipe includes a pipe 52 connected to the nozzle, an elbow 53 connected to the discharge end of the pipe 52, a pipe 54 connected to the elbow 53, an elbow 55 connected 70 to the pipe 54, and a pipe 56 connected to the elbow 55, as is necessary to get out of the secondary pit 57. The upper face 58 may be the normal bottom of the pit and the secondary pit 57 is dug below the level of the 75 bottom 58 simply as a place to put the pump jet nozzle apparatus. In operation this apparatus will discharge all of the liquid above the intake end of the nozzle.

This apparatus might be set in a sump 80 hole containing oil and water for the purpose of skimming the oil off of the water.

Referring to Fig. 4, the nozzle 59 may be the same construction as that shown in Figs. 2 and 3, the essential difference being that 85 the nozzle is set to have the flow opening 60 horizontal with the intake member 61 and the discharge pipe 62 in a straight line.

This construction might be used as a gas burner or oil burner, in which case the power 90 medium would be steam or compressed air or gas, and it may be used for various other purposes such as washing a pipe or hose as it is passed through the opening 60.

95 Referring to the modified form of nozzle shown in Fig. 5, the internally screw threaded pipe nipple 63 is formed integral with the lower casting 64 which has a flaring integral intake. An external thread 65 is formed upon the casting 64 and a rim 66 100 is formed upon the casting 67 to screw upon the threads 65. The members 68 and 69 forming the power medium discharge slot 70 are made separate and applied to the castings so that they may be removed and changed, 105 as when they become worn or when it is desired to make the slot 70 larger or smaller by using thinner or thicker members 68 and 69. The width of the slot 70 may be adjusted to some extent by screwing the casting 67 110 up or down relative to the casting 64.

115 Thus I have produced a pump jet nozzle apparatus having a smooth flow opening for driven material and an annular angular orifice around the flow opening for discharging driving material into the driven material so as to move the driven material through the flow opening.

120 Various changes may be made without departing from the spirit of the invention as claimed.

I claim:

1. A jet nozzle for elevating a liquid comprising in combination a liquid intake pipe, an annular nozzle to conduct another fluid 125 into said intake pipe, said nozzle comprising an annular chamber having two parts, an annular inclined jet opening having an annular opening without obstructions leading into the intake pipe from said chamber, a 130

screw threaded connection between the two parts of the chamber whereby the nozzle faces may be adjusted towards and from each other, and having removable and replaceable faces for the jet opening.

5 2. A jet nozzle for elevating a fluid comprising a pipe having a flange thereon, external threads on the flange, an annular recess between the exterior of the pipe and the flange, an inclined edge from the recess to the interior of the pipe, a complementary pipe having a flange, an internal thread on the flange to engage the first mentioned thread, a recess inside the flange, an inclined 10 annular edge leading from the recess into the pipe, the whole forming in combination an annular jet leading from an exterior channel formed by the complementary recesses and complementary inclined faces, and an 15 aperture for leading a fluid into the channel.

20 3. A jet nozzle as claimed in claim 2 having detachable and replaceable facings on the inclined nozzle faces.

5 In testimony whereof I have signed my name to this specification.

CHARLES B. REYNOLDS.
